UNITED STATES PATENT OFFICE

JOSEPH SICILIANI, OF CHICAGO, ILLINOIS

DESIGN FOR A CONTAINER FOR CANDY OR THE LIKE

Application filed April 18, 1931. Serial No. 39,551. Term of patent 14 years.

To all whom it may concern:

Be it known that I, JOSEPH SICILIANI, a citizen of the United States, residing at Chicago, county of Cook and State of Illinois, have invented a new, original, and ornamental Design for Containers for Candy or the like, of which the following is a specification, reference being had to the accompanying drawings, forming a part thereof, wherein—

Fig. 1 is a perspective view of the container as seen from above;

Fig. 2 is a perspective view of the container as seen from below.

I claim:

The ornamental design for a container for candy or the like, as shown.

JOSEPH SICILIANI.
